SUCTION NOZZLE

Gustaf Erik Björkman, Stockholm, Sweden, assignor to Electrolux Corporation, Dover, Del., a corporation of Delaware

Application July 3, 1936, Serial No. 88,717
In Germany July 8, 1935

7 Claims. (Cl. 15—155)

The present invention relates to suction nozzles for use in connection with vacuum cleaners, and more particularly to a suction nozzle having a suction opening the size of which may be altered at the will of the operator.

For removing the ordinary dirt found on and in a floor covering, it is desirable to have a comparatively large nozzle opening in order that a maximum amount of surface may be covered in a minimum of time. However, certain articles, such as threads, dog hairs, lint and the like tend to adhere to the surface of the covering with such tenacity that they are not removed by the air flow through a nozzle having a comparatively large opening, but may be removed if the velocity of air flow is increased. Such increase may be best effected by decreasing the area of the suction opening.

Among the objects of the present invention is to provide a nozzle in which the size of the suction opening may be altered at will and without removing the nozzle from one surface being cleaned.

Further objects and advantages of the invention will be apparent from the following description considered in connection with the accompanying drawing which forms a part of this specification, and of which:

Fig. 1 is a view of a nozzle in accordance with the present invention attached to a vacuum cleaner unit;

Fig. 2 is a bottom view of the nozzle shown in Fig. 1;

Fig. 3 is a cross-sectional view taken on the line 3—3 of Fig. 2;

Fig. 4 is a cross-sectional view similar to Fig. 3, but showing certain of the parts in a different position;

Fig. 5 is a front view, partially in cross section of the nozzle shown in the preceding figures; and

Fig. 6 is a perspective view of one of the elements of the afore shown nozzle.

Referring more particularly to Fig. 1, reference character 10 designates a vacuum cleaner unit including a dust bag 11 and a motor fan unit 12. Secured to the inlet of unit 10 is a preferably flexible hose 13, the end of which is secured to a rigid hollow handle member 14 to which is in turn secured a suction nozzle 15.

Nozzle 15 includes a member 16 formed with lips 17 adapted to contact the surface to be cleaned. Member 16 is formed at either end with vertically extending portions 18 between which portions is slidably mounted an elongated member 19. The ends of member 19 are solid, while

the central portion thereof is formed with an opening 20. The solid ends of member 19 are provided with grooves 21 into which extend pins 22, rigidly fastened in portions 18. A spring 23 is also disposed in groove 21 and is stressed between member 19 and pins 22, thus tending to maintain the member 19 in the elevated position shown in Figs. 3 and 5.

Member 19 is guided in its up and down movement by pairs of angularly shaped vertically extending members 24, each consisting of a lug 24' running substantially perpendicularly to the longitudinal axis of member 16 and a wall 24'' running between lug 24' and portion 18 in parallel with said axis. Members 24 are secured to or integral with member 16. Members 24 constituting each pair are disposed on opposite sides of member 19 while the pairs of lugs are spaced from each other and from the ends of the member so as to divide the lengthwise extent of the member 16 into three substantially equal sections. The solid end portions of member 19 terminate at lugs 24' and the opening 20 through member 19 is disposed entirely between the lugs.

Pivottally mounted between lugs 24' are wall 25 members 25. Springs 26 are secured to the solid end portions of member 19 by means of screws 27, these springs being disposed between the pivoted members 25 so as to tend to maintain them in substantially vertical positions, as shown in Fig. 3, with the upper inner edges of the members 25 in contact with downwardly extending walls 28 integral with the central portion of member 19 and forming part of the boundary of the opening 20 therethrough. This central portion of member 19 is also provided with inclined walls 29.

A hollow member 30 is connected to member 19 so as to be pivotable about a substantially horizontal axis. Member 30 has an inner cylindrical surface adapted to rotate on a similar cylindrical surface 31 formed on the upper part of member 19. Lateral extensions 32 are integral with member 30 and are received beneath cap members 33 secured to member 19, thus rotatably fastening member 30 to member 19. Member 30 is adapted to receive the end of hollow handle member 14.

The operation of the above described device is as follows:

With the parts in the position shown in Figs. 3 and 5, rotation of the motor fan unit 12 causes air to be drawn in through nozzle 15, handle 14 and hose 13 to within the dust bag 11. Any dust entrained with this air is deposited within

the dust bag and the purified air passes through the material of the dust bag and is discharged from the unit.

With the parts in the aforesaid position, air is drawn into member 30 through the opening 20 in member 19. With the part 19 in the elevated position with respect to member 18, suction openings 34 are formed at either end of the nozzle. These openings are bounded at the top by member 19 and are bounded at both sides and their outer ends by fixed walls formed by member 18, their inner ends being open to the passage 20 in member 19. Inasmuch as the nozzle opening bounded by the pivoted wall members 25 is in direct communication with opening 20, air will be drawn into the nozzle throughout its entire length, thus enabling the nozzle to clean a comparatively wide strip during each stroke of the nozzle. The air flow through this large opening is sufficient to remove the ordinary dust and dirt embedded in and adhering to the surface undergoing cleaning.

In the event that this air flow is not able to remove some articles found on the surface, the operator bears down on handle 14, thus moving member 19 downwardly with respect to body 18 against the force of springs 23. This movement of member 19 causes the solid end portions thereof to completely close and fill up the end portions 34 of the nozzle opening, thus preventing air flow therethrough. Also, the downward movement of member 19 causes the pivoted wall members 25 to be turned to the position shown in Fig. 4, by virtue of the fact that the upper edges of these pivoted members will slide along to the inclined surfaces 29. This pivoting of members 25 causes their lower edges to approach each other, thus decreasing the width of the opening therebetween.

Consequently, the length of the effective nozzle opening not only has been reduced by approximately two-thirds, but the width of the remaining one-third of the opening has been decreased. This results in an increase in the velocity of air flow through this opening which is able to pick up articles which strongly adhere to the surface undergoing cleaning.

The pivotal connection between members 19 and 30 makes it possible to lower the handle 14 toward a substantially horizontal position in order to manipulate the nozzle under furniture. Moreover, this pivoting of the handle does not affect the size of the suction opening.

It will thus be seen that with the nozzle here-
in illustrated and described, the effective size of the suction opening may be reduced by the operator at will without removing the nozzle from the surface undergoing cleaning.

Although I have shown a more or less specific embodiment of my invention, it is to be understood that this has been done for purposes of illustration only and that the scope of my invention is to be limited only by the appended claims viewed in the light of the prior art.

65 What I claim is:

1. In a suction nozzle, a body member formed with a suction opening having a portion bounded by fixed wall structure and a portion bounded in part at least by pivotally mounted side wall structure, and means for closing the portion of said opening bounded by said fixed wall structure and for moving said pivotally mounted wall structure inwardly towards the center of said opening to reduce the area of the portion of said opening bounded thereby.

2. In a suction nozzle, a body member formed with a suction opening having a portion defined by fixed wall structure and a portion defined in part at least by pivotally mounted side wall structure, and a member displaceably mounted with respect to said body member and displaceable to close the portion of said suction opening defined by said fixed wall structure and to move said pivotally mounted wall structure inwardly towards the center of said opening to reduce the area of the portion of said suction opening defined thereby.

3. In a suction nozzle, a body member formed with an elongated suction opening, the end portions of said opening being defined by fixed walls, pivotally mounted walls defining the central portion of said opening, and a member reciprocably mounted with respect to said body member and movable in one direction to close said end portions and to turn said pivotally mounted walls to reduce the area of said central portion.

4. In a suction nozzle, a body member formed with a suction opening having a portion defined by fixed wall structure and a portion defined in part at least by pivotally mounted wall structure, a member mounted for movement in a vertical direction with respect to said body member, resilient means urging the movable member upwardly, and a handle secured to said movable member and adapted to move the latter downwardly to close the portion of said suction opening defined by said fixed wall structure and to move said pivotally mounted wall structure to reduce the area of the portion of said suction opening defined thereby.

5. In a suction nozzle, a body member formed with a suction opening having a portion defined by fixed wall structure and a portion defined in part at least by pivotally mounted wall structure, a member mounted for movement in a vertical direction with respect to said body member, resilient means urging the movable member upwardly, and a hollow rigid handle member pivotally secured to said movable member for connecting said nozzle to a source of suction and for moving said nozzle on a surface to be cleaned, said handle being adapted and arranged to transmit downwardly directed force to said movable member for moving the latter downwardly to close the portion of said opening defined by said fixed wall structure and to move said pivotally mounted wall structure to reduce the area of the portion of said suction opening defined thereby.

6. In a suction nozzle, a body member formed with a suction opening having a portion bounded by fixed wall structure and a portion bounded in part at least by pivotally movable wall structure, flow preventing means movable into the portion of said opening bounded by said fixed wall structure, and means for moving said movable wall structure to reduce the area of the portion of said opening bounded thereby.

7. In a suction nozzle, a body member formed with a suction opening having a portion bounded by fixed wall structure and a portion bounded in part at least by pivotally movable wall structure, and a flow preventing member reciprocably mounted with respect to said body member and movable into the portion of said opening bounded by said fixed wall structure for blocking flow therethrough and for moving said movable wall structure to reduce the area of the portion of said opening bounded thereby.
